X-MEMBER

Einar Almdale, Detroit, Mich., assignor to The
Midland Steel Products Company, Cleveland,
Ohio, a corporation of Ohio

Application April 26, 1940, Serial No. 331,779

8 Claims. (Cl. 280—106)

This invention relates to new and useful improvements in structural members of the type shown in my copending application Serial No. 325,212, filed March 21, 1940.

An important object of the invention is to further simplify the construction of the X-shaped or cruciform member shown in this application by forming the intersection piece of the member with stampings separate from the arms of the X-member, which arms may face either inwardly or outwardly of the vehicle frame with which it is associated.

Another important object of the invention is to provide an open top cradle-shaped piece for an X-member which may be formed from two simple stampings.

Other objects and advantages of the invention will become apparent during the course of the following description, wherein like numerals are employed to designate like parts throughout the several views.

In the accompanying drawing forming a part of the application,

Fig. 1 is a perspective view of the improved center or intersection piece of the X-member,

Fig. 2 is a transverse section of the same,

Fig. 3 is a view similar to Fig. 2 but showing the sub-rails extending through the center piece instead of being butt welded to the ends thereof,

Fig. 4 is a transverse section of the intersection piece for sub-rails having inwardly facing channels,

Fig. 5 is a top plan thereof,

Fig. 6 is a modified form of intersection member with inwardly facing sub-rails cooperating in forming the enclosed box section center piece.

As explained in my copending application, these X-members for vehicle frames must be provided with openings through their intersection pieces for appropriate clearance and movement of the usual inclined propeller shaft of a motor vehicle which extends from the rear end of the transmission to the differential of the rear wheels. Generally in this type of X-member, the intersection piece is provided with an opening bounded upon all sides, including its top and bottom with metal which in certain makes of automobiles, requires a tunnel or raised portion in the floor of the passenger compartment. The present invention obviates the necessity of providing this tunnel or raised portion by a unique construction of the intersection piece of the X-member.

The two forwardly diverging arms of the X-member are designated by the numeral 10, while

the rearwardly diverging arms of such members are designated by the numeral 11. These arms are usually constructed of outwardly facing channel beams, in order to cooperate with the side rails of the vehicle frame in forming such rails into completely closed box section, but these arms may also be reversed so that their channels face in the opposite direction, namely toward the longitudinal center line of the frame, or may be hollow and of any desired section best suited to the requirements of the particular frame.

In the form of invention shown in Figs. 1 to 5 inclusive, the intersection piece is composed solely of two simple stampings to form a hollow, substantially rectangular casing having a socket at each of its four corners for connection with the arms of the X-member, and a relatively wide deep groove in its top extending lengthwise of the frame and casing to provide propeller shaft clearance, and in effect an open top cradle shaped intersection piece.

The lower half of this intersection piece is a substantially rectangular stamping 12 having its four corners extended as at 13 and provided with upstanding side flanges 14 which are continued from corner to corner to form boundary flanges and attaching means. This construction leaves the extended radial corner portions of U or channel shape in cross section.

The upper part of the intersection piece is composed of a single inverted U-shaped stamping 15 having the same outline as the lower stamping but with depending side walls 16 of much greater height than the flanges 14 to be vertically aligned therewith and butt welded thereto as at 17, although the attachment of these walls may be made in any desired manner. This construction provides each end of the intersection piece with a pair of outwardly diverging rectangular socket members 18 to which channel section or box section arms 10 and 11 of the X-member may be butt welded as at 19. The top of this rectangular intersection casing is provided with a relatively wide and deep depression or groove 20 extending lengthwise thereof from one end thereof to the other to provide the requisite propeller shaft clearance.

In Fig. 3 is shown a modification of the X-member arms in which the arms 10 and 11 on one side of the intersection piece are not separate pieces of channel section as shown in Fig. 1, but are formed from one piece of channel section which forms both arms 10 and 11 and is extended lengthwise through the hollow intersection piece as a continuous member. In this instance, the

web of the sub-rail which is disposed within the hollow intersection piece is deformed into the shape of the side wall of the groove 20 to snugly engage and support the same as shown in Fig. 3, with the upper and lower flanges of the channel section engaging the top and bottom stampings and being secured thereto as well as to the side of the groove by any suitable means.

In Figs. 4 and 5 the same intersection piece is employed as shown in Figs. 1 and 2, but with the arms 22 of the X-member formed of two channel members having their channels facing inwardly toward the longitudinal center line of the intersection piece and automobile frame, and with the lower portions of these arms which extend longitudinally through the hollow intersection piece, extended laterally along the bottom of stamping 12 as at 23 and then projected at an obtuse angle to provide inclined struts 24 to terminate in tabs or tongues 25 which extend through slots in the bottom of the groove 20 to be welded thereto by keywelds. The top flanges of the X-member arms 22 are secured in any suitable manner to the top of the hollow intersection member and are completely housed therein.

In Fig. 6, the sides of the hollow intersection piece are formed by the intermediate portions of two inwardly facing channels which constitute the four arms of the X-member. The top of the intersection piece in this instance is provided by a U-shaped stamping 26 having its side edges terminating in outwardly extending horizontal flanges 27 which are welded as at 28 to the edges of the upper flanges 29 of the X-member arms 30. A flat plate 31 forms the bottom of the hollow intersection piece and its side edges are welded as at 32 to the edges of the lower flanges 33 of the X-member arms. The two ends of the hollow intersection piece may be closed with imperforate plates 34 which may have integral projections on all four of its edges to extend through slots in the adjacent parts of the intersection piece and the X-member arms to be subsequently key welded thereto and to form the inner section piece into a completely enclosed substantially rectangular housing of the shape shown in Fig. 5.

It will of course be understood that various changes in the size, shape and relation of parts may be resorted to without departing from the spirit of the invention or the scope of the appended claims.

I claim:

1. An intersection member for an X-member for automobiles comprising upper and lower stampings fastened together to constitute by themselves a box section, and the upper stamping having a depressed wide groove extending longitudinally thereof and down between the sides of said member for propeller shaft clearance.
2. An intersection member for a plurality of radiating arms comprising a stamping of inverted U-shape cross section having depending flanges

and having its bridge piece provided with a longitudinally extending depressed portion, and a second stamping secured to the depending flanges of the inverted U-shaped stamping.

5 3. An intersection piece for X-members comprising a substantially rectangular stamping having an extension at each corner and an upstanding flange along the sides of the stamping and the sides of the corner extensions, and a correspondingly shaped stamping having much deeper corresponding flanges secured to those of the first stamping and having a relatively deep wide groove extending the full length thereof, said stampings forming a hollow substantially rectangular casing completely enclosed with the exception of the ends of said corner extensions.

4. An X-member comprising a hollow member having a depressed concaved top portion extending longitudinally thereof, and X-member arms extending into said hollow member and having portions conforming to the shape of the depression and having lateral extensions spaced apart and secured to the side walls of the concaved top.

5 5. An X-member comprising a hollow section intersection member having a top piece formed with a depression extending longitudinally thereof for propeller shaft clearance thereabove, and a pair of channel members, each forming a pair of arms of the X-member at one side thereof and extending longitudinally through the hollow intersection member.

6 6. A structural member for automobile frames comprising a pair of channel sections having portions of their webs substantially parallel to each other and horizontally offset toward one another and spaced apart, means for closing the space between the offset spaced parallel web portions and the lower flanges of said sections, and means for closing the channels of said sections.

7. A structural member comprising a pair of oppositely and outwardly facing channel sections with the upper and lower flanges facing outwardly, the webs of said sections having inwardly extending horizontal offset portions spaced apart, a member connecting said spaced offset portions and having a portion spaced below the top flanges, and a second horizontal member having a portion spaced from the first member and connecting the lower flanges of said sections.

8 A structural member comprising a pair of oppositely and outwardly facing channel sections with the upper and lower flanges facing outwardly, the webs of said sections having inwardly extending horizontal offset portions spaced apart, a member connecting said spaced offset portions and having a portion spaced below the top flanges, a second horizontal member having a portion spaced from the first and connecting the lower flanges of said sections, and said members having portions secured to the upper and lower flanges of said sections for closing the channels thereof.

EINAR ALMDALE.
